FIG. 1 is a plan view of an apertured prismatic cover plate for climate lights showing my new design;

FIG. 2 is a vertical sectional view taken on a plane parallel to a side of FIG. 1 and passing through the center of two of the apertures therein;

FIG. 3 is a vertical sectional view taken on a corner-to-corner diagonal plane in FIG. 1;

FIG. 4 is an other embodiment of my new design in plan view;

FIG. 5 is a vertical sectional view taken on a plane parallel to a side of FIG. 4 and passing through the center of two of the apertures therein;

FIG. 6 is a vertical sectional view taken on a corner-to-corner diagonal plane in FIG. 4;

FIG. 7 is another embodiment of my new design in plan view;

FIG. 8 is a vertical sectional view taken on a plane parallel to a side of FIG. 7 and passing through the center of two of the apertures therein;

FIG. 9 is a vertical sectional view taken on a corner-to-corner diagonal plane in FIG. 7;

FIG. 10 is another embodiment of my new design in plan view;

FIG. 11 is a vertical sectional view taken on a plane parallel to a side of FIG. 10 and passing through the center of two of the apertures therein; and

FIG. 12 is a vertical sectional view taken on a corner-to-corner diagonal plane in FIG. 10.

I claim:

The ornamental design for an apertured prismatic cover plate for climate lights, as shown and described.
